RAILWAY AXLE LUBRICATOR STRUCTURE

James J. Hennessy, Montclair, N. J.

Application December 16, 1940, Serial No. 370,264

3 Claims. (Cl. 308—80)

The invention relates to the lubrication of railway axle journals and more particularly to the recovery of surplus oil supplied to the journals of railway driver axles.

The present application is a continuation-in-part of an application filed April 18, 1940, Serial No. 330,242.

The invention is used in connection with mechanical lubricators whereby oil is pumped to the journal. Such lubricators are designed to feed an adequate supply of lubricant to the journal under unfavorable conditions, for example, when low temperature reduces the fluidity of the lubricant, and when slow movement of the vehicle or minimum play of the axle longitudinally of the box provides a comparatively slight pumping action. Hence, when the conditions are more favorable for pumping the lubricant, there will be an excess amount of lubricant supplied to the journal and this excess lubricant tends to travel longitudinally of the journal beyond the bearing surfaces and to escape from the box and be wasted.

The main object of the present invention is to reduce such loss at the rear of the box and bearing by trapping such surface lubricant and returning it to the lubricant cellar or reservoir from whence it may be pumped again to the journal.

This and other detailed objects of the invention are attained by the structure illustrated in the accompanying drawing in which—

Figure 1 is a vertical longitudinal section through a locomotive driver axle box and bearing, and associated structure for preventing the loss of lubricant, the journal and adjacent portions of the wheel hub and axle and the mechanical lubricator being shown in elevation.

Figure 2 is a transverse cross section taken on the line 2—2 of Figure 1.

The axle 1 includes a journal 2 and mounts the driving wheel, having the hub 3, in the usual manner. A bearing 4 rests upon the journal and supports a box having the top wall 5 and end liner 6.

A cellar and lubricant reservoir 8 is applied to the lower portion of the journal and is carried upon a plate 7 extending between the side walls 1 of the axle box. Cellar 8 extends rearwardly of plate 7 and the box side walls and journal 2, and at one side is provided with a sump 9 having a valve 9a whereby water may be collected and drained from the reservoir.

A lubricating device is mounted in cellar 8 and includes a pump actuated by the play of the axle 55

longitudinally of the box whereby lubricant is fed from the cellar through a conduit 10 to the lower face of the journal and is distributed over the latter by suitable pads 11.

5 The details of the pumping structure are well known to those skilled in the art and will not be further described here.

Oil supply to the journal is fed under bearing 4 by the upwardly moving side of the journal and forms a film upon which the bearing rests. Surplus oil is squeezed longitudinally of the journal. That portion flowing to the front of the journal is recaptured by the "wipers" indicated at 12 and by a trough 13 detailed and described in the above-mentioned application Serial No. 330,242.

10 The axle is provided with a neck 16 of slightly less diameter than the journal and the remainder of the axle. Preferably the journal extends somewhat beyond the rear end of bearing 4, and a packing strip 20 of leather, felt or similar material is applied to the box rear wall and overlies the shoulder 21 formed at the junction of journal 2 and neck 16.

15 A semi-circular housing 17 encloses the upper part of neck 16 and is flanged at 17a for attachment to the rear wall of the driving box by bolts 18. The lower edges of the sides of housing 17 overlap the upper edges of the sides of cellar 8, and the rear end of housing 17 terminates in a downturned lip 19 fitting within the rear wall of the cellar. Strips 17a welded to the lower edges of the housing direct oil to the interior of the cellar.

20 A reenforcing partition plate 22 extends across the rear portion of cellar 8 and is apertured to position pin 26, and plate 22 and the rear portion of the cellar are further reinforced by cross plate 27.

25 Any oil escaping at the rear end of the journal past packing 20 is deflected to neck 16 which is of such length that before the oil travels to the rear thereof it forms a peripheral ring which will break up into drops and will drop onto plate 22 or will be discharged by centrifugal force against the side 30 of housing 17 or the side wall of the cellar and will flow down to plate 22 and then drain, through openings 28 in plate 22, back to the reservoir where it may be again pumped to the journal.

35 If any oil flows the full length of neck 16, it will be thrown off onto the housing or cellar side wall when it reaches shoulder 23. The cellar and housing 17 extend beyond shoulder 23 and their inturned rear elements tend to baffle the entrance of dirt, water, etc., to the interior of the housing,

but these elements are not necessary to prevent the loss of oil.

Preferably a wiper 24 is applied to the lower rear portion of journal 2 and extends rearwardly of the same and is thrust against same by the spring 25 seated on the bottom of cellar 8 and supporting a pin 26 which mounts the wiper.

While all of the elements shown have been used together to advantage, it will be understood that the general principle of the invention may be involved if some of the parts are omitted. For example, if packing 20 and wiper 24 were not present, the functioning of neck 16 and housing 17 would be substantially as described above. The exclusive use of the structure as described or in any modified form which comes within the scope of the appended claims is contemplated.

What is claimed is:

1. In combination, a railway vehicle axle box, a journal bearing secured therein, an axle having a journal supporting said bearing and box, said axle including a neck portion of less diameter than said journal and extending rearwardly from said journal and from the rear of said box and bearing, a removable lubricant cellar carried in said box beneath said journal, there being a device in said cellar for pumping lubricant therein to said journal, said cellar including bottom and side walls extending rearwardly of said journal, bearing and box, said side walls extending upwardly alongside of said journal and neck, and a housing secured to the rear of said box and extending therefrom over said neck and downwardly at the sides thereof and terminating in forked elements receiving between them the upper edges of the cellar side walls, said housing and the rearwardly extending portion of said cellar comprising structure for collecting surplus lubricant escaping from the rear of said bearing and returning the same to said device.

2. In combination, a railway vehicle axle box, a journal bearing secured therein, an axle having a journal supporting said bearing and box, said axle including a neck portion of less diam-

eter than said journal and extending rearwardly from said journal and from the rear of said box and bearing and forming a shoulder at the rear of the journal, a removable lubricant cellar carried in said box beneath said journal, there being a device in said cellar for pumping lubricant therein to said journal, said cellar including bottom and side walls extending rearwardly of said journal, bearing and box, said side walls extending upwardly alongside of said journal and neck, and a housing secured to the rear of said box and extending therefrom over said neck and downwardly at the sides thereof to meet the sides of said cellar, there being a packing between the housing and the rear end of the journal box and bearing and overlying and contacting the shoulder between the axle neck and the rear end of the journal and extending over the top and downwardly along the sides of the axle to a point near the top edges of the cellar side walls.

3. In combination, a railway vehicle axle having a journal and a neck of reduced diameter adjacent thereto, a journal bearing extending lengthwise of the journal substantially throughout the length of the latter, a lubricant cellar beneath said journal and including a part extending beneath the axle and rearwardly of said journal, bearing and neck, a device in said cellar for pumping lubricant to the journal, and a housing extending from said journal above said neck and downwardly at the sides thereof to meet the rearwardly extending part of said cellar, whereby lubricant discharged centrifugally from said neck will be trapped by said housing and the adjacent portion of said cellar, and a drain for leading said trapped lubricant back to said cellar, there being a flexible packing secured to the portion of said housing adjacent the journal and bearing against the shoulder formed by said neck and extending over the upper and side portions of the neck to check the escape of oil from the journal.

JAS. J. HENNESSY.
